Attorney, Agent, or Firm—Stanley G. Ade

[57] CLAIM

The ornamental design for a combined bathtub and shower enclosure, as shown and described.

DESCRIPTION

FIG. 1 is a front elevational view of a combined bathtub and shower enclosure showing my new design;

FIG. 2 is a rear elevational view thereof;

FIG. 3 is a top plan view thereof;

FIG. 4 is a cross sectional view taken on line 4—4 of FIG. 1;

FIG. 5 is a cross sectional view taken on line 5—5 of FIG. 3 with the bottom panel omitted for convenience of illustration;

FIG. 6 is a cross sectional view taken on line 6—6 of FIG. 1;

FIG. 7 is a front elevational view of a modified form of the combined bathtub and shower enclosure shown in FIG. 1;

FIG. 8 is a top plan view of FIG. 7;

FIG. 9 is a cross sectional view taken on line 9—9 of FIG. 7; and

FIG. 10 is a cross sectional view showing the top portion of the enclosure taken on line 10—10 of FIG. 8.
